UNITED STATES PATENT OFFICE.

HANS C. HANSON, OF ALBERT LEA, MINNESOTA.

VAPOR-BURNER.

1,207,031.

Specification of Letters Patent.

Patented Dec. 5, 1916.

Application filed March 20, 1916. Serial No. 85,339.

To all whom it may concern:

Be it known that I, HANS C. HANSON, a citizen of the United States, residing at Albert Lea, in the county of Freeborn and State of Minnesota, have invented a new and useful Improvement in Vapor-Burners, of which the following is a specification.

This invention relates to improvements in burners, and more particularly to that class in which a hydrocarbon liquid such as gasolene, kerosene, alcohol and other oils or spirits are vaporized and mixed with air, said mixture being supplied to a mantle.

Among the objects of this invention is to provide a burner, which is simple and inexpensive in construction and efficient and economical in operation.

Another object is to provide a burner, the parts of which can be easily disassembled for the purposes of cleaning and repairing when necessary and by which the constituent parts of the fuel mixture may be readily adjusted so as to produce a steady and maximum amount of light.

Further objects will be apparent from the following description.

To these ends my invention comprises the features of construction and combination of parts hereinafter more particularly described and claimed.

In the drawing forming part of this specification, Figure 1 is a side elevation of my improved burner, parts of the structure being broken away and in section; Fig. 2 is a section taken on the line X—X of Fig. 1; Fig. 3 is a section on the line Y—Y of Fig. 1, and Fig. 4 is a perspective of the removable auxiliary generator forming part of the invention.

In the drawing A indicates the main vapor generator which is in the form of an upright tube having connected to its lower end, by the coupling 2, a valve B, which controls the supply of fuel from the pipe 3 to the main generator, said pipe leading to any source of fuel such as gasolene under pressure not illustrated.

Mounted upon the upper end of the main generator tube is a burner head C having a horizontal body portion 4 turned downwardly at each of its ends, one end 5 having an internal thread 6. Secured to the end 5 by an externally threaded collar 7 is a mantle holder 8 of usual construction upon which is secured in any well known manner a mantle 9 of usual form. The opposite end 10 of

the burner head terminates in a depending Bunsen tube 11, the passage through which extends upwardly and longitudinally through the burner head and downwardly into the mantle. The lower end of the Bunsen tube has formed in its side an air admission opening 12, the size of which may be regulated by turning a collar 13, having a threaded connection about the lower end of the Bunsen tube over said opening. The lower end of the tube 11 is closed by a transverse wall 14 arranged a short distance above its lower extremity, said wall being formed with a centrally disposed opening 15. Associated with said parts is an auxiliary vapor generator 16 in the form of a long thin tube having on its upper end a connecting head 17 of cylindrical form having one end formed with a conical point 18 and its other end with a concave seat 19. A passage 20 connected with the inlet end of the tube 16 extends longitudinally through the conical end 18 of the head. The lower end 21 of the tube 16 is closed and has secured thereon a cylindrical member 22 having a passage 23 connected with the passage in said tube. The upper end of the cylindrical member 22 is formed with a small orifice 24. Arranged within the passage 23 is a cleaning needle 25, which is slidably mounted in a packing member 26 through which a stem 27 extending downwardly from the needle slides. A cap nut 28 threaded on the cylindrical member 22 comprises the packing member 26 and completes the formation of a gland through which the needle member is adapted to slide. A link 29 secured to the lower end of the stem 27 is adapted for sliding the cleaning needle back and forth. The point of the cleaning needle is adapted to enter the orifice 24 when the needle is pushed upwardly to remove any foreign substances and clean said orifice from time to time as desired.

A side of the burner head is formed with two supporting lugs 30 and 32 spaced apart and between which the head 17 is admitted. The lug 30 is formed with a passage 31, which is adapted to form a connection between the passages 20 in the head 17 and the main vapor generator tube A. The upper end of the auxiliary generator is supported by its conical end 18 entering a socket seat 33 in the lug 30, the shank of a set bolt 34 being threaded in the other lug 32 and entering the concavity 19 for hold-

ing the head 17 seated. When so seated, it will be seen by reference to Fig. 1 that a tight passage is formed between the main and auxiliary generators. The lower end 5 of the auxiliary vaporizing tube 16 is formed with an elbow 35, so that in use the main portion of the tube 16 depends from alongside of the burner head and its lower end extends through a slot 36 and into an opening or socket seat 37 in the lower extremity of the Bunsen tube with the nozzle 38 of the cylindrical body 22 entering the opening 15 in the wall 14, said auxiliary vapor generator being held or interlocked securely at 10 its lower end in said position thereby. Both the main and auxiliary generator tubes are arranged in close proximity to the mantle 9, so that the heat generated by the mantle will heat said tubes, and cause efficient 15 vaporization of the fuel, and more thorough mixing of the fuel constituents in the Bunsen tube. The main vapor generator contains a wick 40 of straining material made of asbestos or other suitable material, which 20 collects any foreign substances in the liquid fuel, which is admitted by the valve B into the burner and retards its flow somewhat, so that an excessive amount of liquid fuel is prevented from entering the tube 16. 25

30 In operation heat is applied to the elbow 35 such as by holding a lighted match in proximity thereto. The fuel supply valve B is then gradually opened, heat being applied to the elbow until gas will ignite over 35 the mantle 9. The regulating collar 13 is adjusted, so that the proper amount of air entering the opening 12 mixes with the gas or fuel which is admitted through the orifice 24 to produce a brilliant light by the 40 mantle. Should the orifice 24 give any indication of clogging such as by uneven burning of the gas, the cleaning needle 25 is pushed up into the orifice and pulled down again quickly while the lamp is burning. 45 This is repeated as often as is necessary until the mantle burns steadily. To avoid any gas escaping from leaking joints, the nut 28 and bolt 34 are tightened. When it is desired to clean the main generator, the 50 nut 2 is loosened, and the tube A and wick 40 removed. The wick is then washed in gasolene or other suitable medium or replaced by a new wick and the parts re-assembled. To clean or replace the auxiliary generator, the bolt 34 is loosened and the generator tipped forwardly and down until the end 21 and cylindrical member 22 slip out of their 55 sockets in the Bunsen tube.

In accordance with the patent statutes, I 60 have described the principles of operation of my invention, together with the apparatus which I now consider to represent the best embodiment thereof, but I desire to have it understood that the construction shown is only illustrative, and that the in-

vention can be carried out by other means and applied to uses other than those above set forth within the scope of the following claims.

Having described my invention, what I claim as new and desire to protect by Letters Patent is:—

1. A vapor burner, comprising, in combination, a main vapor generator extending upwardly, a burner head mounted upon said generator having its ends extending downwardly and formed with a longitudinal passage, one of said ends having a mantle holder and its other end having a depending Bunsen tube, an auxiliary vapor generator extending downwardly from said head having a passage connected with the upper end of said main generator and with the lower end of said Bunsen tube, said auxiliary generator being removably mounted upon said head and Bunsen tube, and said generators being arranged in close proximity to said mantle support. 80

2. A vapor burner, comprising, in combination, a main vapor generating tube extending upwardly, a burner head mounted upon said tube having its ends extending downwardly and formed with a longitudinal passage, one of said ends having a mantle support and its other end having a depending Bunsen tube, an auxiliary vapor generating tube extending downwardly from said head having its passage connected with the upper end of said main generating tube and with the lower end of said Bunsen tube, said auxiliary tube being removably seated in said Bunsen tube, and a coupling removably securing the auxiliary tube to said head, said tubes being arranged adjacent to each other and to said mantle support. 100

3. A vapor burner, comprising, in combination, a main vapor generator extending upwardly, a burner head mounted upon said generator having its ends extending downwardly and formed with a longitudinal passage, one of said ends having a mantle holder and its other end having a depending Bunsen tube, an auxiliary vapor generator extending downwardly from said head having a coupling member on its upper 110 end removably socketed in said burner head and connected with the upper end of said main generator and a gland member on its lower end removably socketed in the lower end of said Bunsen tube and having an orifice from said auxiliary generator entering said Bunsen tube, and means for holding the head of said auxiliary generator socketed in said burner head, said generators being arranged in close proximity to the 125 mantle carried by said mantle support.

4. A vapor burner, comprising, in combination, a main vapor generator extending upwardly, a burner head mounted upon said generator having its ends extending down- 130

- wardly and formed with a longitudinal passage, one of said ends having a mantle holder and its other end having a depending Bunsen tube, said Bunsen tube having 5 an upward opening into its lower end, a laterally extending socket seat in said tube adjacent said upward opening and a slot opposite said socket seat, and an auxiliary vapor generator extending downwardly from 10 said head having a coupling member on its upper end removably attached to said burner head and connected with the upper end of said main generator and a gland member on its lower end entering said upward opening 15 and formed with an orifice from said auxiliary generator entering said Bunsen tube, the lower end of said auxiliary generator being held in said slot and said socket seat adjacent to said upward opening and 20 said generators being arranged in close proximity to said mantle support.
5. In combination with a vapor burner having a Bunsen tube, an auxiliary vapor generating tube associated with said burner 25 to be heated thereby, having a coupling on its upper end for detachably connecting it with said burner and having its lower end shaped to form a removable socket connection with the lower end of and having a 30 nozzle entering said Bunsen tube, and means carried by said auxiliary tube for cleaning the orifice in said nozzle.
6. A vapor burner, comprising, in combination, a main vapor generator extending 35 upwardly, a burner head mounted on said generator having its ends extending downwardly and formed with a longitudinal passage, one of said ends having a Bunsen
- tube, a mantle holder on an end of said head opposite said tube, an auxiliary vapor 40 generator removably connected by its upper end with the upper end of said main generator to form a continuous vapor passage and its lower end in interlocking connection with said Bunsen tube and formed 45 with a nozzle having an orifice entering said Bunsen tube and means carried by said tube for cleaning said orifice, said generators being arranged adjacent to said mantle.
7. A vapor burner, comprising, in combination, a main vapor generator extending upwardly, a burner head mounted upon said generator having its ends extending downwardly and formed with a longitudinal 50 passage, one of said ends having a mantle holder and its other end having a depending Bunsen tube, said head having a 55 passaged socket seat connected with said longitudinal passage and a lug adjacent to said seat and said Bunsen tube having a 60 socket seat and an upward passage in its lower end, an auxiliary vapor generating tube disposed adjacent to said main generator and having a socket member on its upper end seated in the socket seat in said head and its lower end seated in the socket seat in said Bunsen tube and in said upward passage, said lower end being formed with 65 an orifice entering said Bunsen tube, and a screw threaded in said lug and pressing against said socket to removably hold the latter in its seat.
- In testimony whereof, I have signed my name to this specification.

HANS C. HANSON.
